ATTORNEY.

UNITED STATES PATENT OFFICE.

JAMES S. HULL, OF LOS ANGELES, CALIFORNIA.

BUILDING CONSTRUCTION.

Application filed January 28, 1921. Serial No. 440,598.

To all whom it may concern:

Be it known that I, JAMES S. HULL, a citizen of the United States, residing near Los Angeles, in the county of Los Angeles and State of California, have invented new and useful Improvements in Building Construction, of which the following is a specification.

This invention relates to building construction, and more particularly to the construction of buildings comprising a plurality of blocks of concrete, cement or other suitable building material which blocks are preferably united by means of cementitious material. The invention has for its object to provide improvements in construction of the general nature stated, whereby structures such as houses, walls, silos and in fact any structures within the wide range of adaptability of the invention, may be readily reared or assembled, even by unskilled labor; to this end suitable interfitting blocks are provided, which blocks may be first properly assembled upon a suitable foundation, in conformity with the preconceived plan of the builder, after which such blocks may be united by posts or keys of cementitious material poured from above into a suitable preferably vertically extending space provided for in the formation of the blocks at adjacent interfitting ends or sides. After the cementitious posts have set, an enduring structure with securely united portions is had. In addition to the vertically disposed posts, I may form a continuous horizontal upper sill, which surmounts the blocks and which may be conveniently formed of cementitious material poured as the posts are poured and so being integral therewith when the material has set or hardened.

A further object of the invention is to provide a building block adapted for use in structures as above outlined which is provided with suitable means whereby the same may be interfitted or interengaged with other and similar blocks, and which means are suitably formed to provide a space for the key or post to be introduced between adjacent blocks; and whereby a reversible block is produced.

With the above and other objects in view, the invention consists in the novel and useful provision, formation, construction, com-

bination, association and relative arrangement of parts, members and features, all as hereinafter described, shown in the drawing, and finally pointed out in claims. This application is a continuation in part of applicant's application Serial No. 279,333, filed February 26, 1919.

In the drawing:

Figure 1 is a fragmentary perspective view of building construction, illustrating a mode of assembling several features of the invention;

Figure 2 is an enlarged plan view of a building block constructed in accordance with the invention;

Figure 3 is a central longitudinal sectional view taken on the line 3—3 Figure 2;

Figure 4 is an enlarged fragmentary perspective view showing the conformation of the corner post or key in the completed structure;

Figure 5 is a plan view of a corner block; and

Figure 6 is a plan view showing blocks embodying a slightly modified form of the invention.

The parts in the several figures are designated by reference characters.

Referring with particularity to the drawing, in Figures 1, 2, 3, 4 and 5 thereof, A, B and C and D, designate, in each instance, building blocks embodying the invention. E designates in each instance, a post uniting adjacent blocks, F designates a foundation, and G designates a sill crowning the wall structure built up of blocks.

The blocks A, the details of which will be readily understood by reference to Figures 2 and 3, are preferably rectangular in form, each having a side wall 8, a side wall 9, an end wall 10, and an end wall 11, so providing a hollow, light and strong building block open from top to bottom, providing an air hollow between the walls of the block. The end wall 10 is preferably provided with spaced vertically extending flanges 12 each of which is preferably spaced a slight distance inwardly of the respective corner of the block; these flanges 12 are shown as extending the full height of the block, that is, from top to bottom of the same, and as having converging sides as at 12^a, Figure 3, and so being of triangular cross-section. At the end wall 11 the block is provided with an

extension 8^a of the side wall 8, and an extension 9^a of the side wall 9; the outer faces of such extensions are continuations of the outside faces of the respective side walls, 5 while the inner faces of such extensions are angularly disposed with respect to the outside faces of the block and diverge outwardly from the end wall 11 so providing a vertically disposed recess 11^a at the end 10 of the block opposite the flange-carrying end, such recess being, due to its complementary formation, adapted to receive the flanges 12 of a similar block when such blocks are laid end to end.

15 The blocks B are formed exactly like the blocks A but are a trifle shorter, in order that a structure similar to that shown in Figure 1, with blocks laid in break-joint formation, or staggered relation may be conveniently reared, by employing blocks such as A and B in conjunction with corner blocks C, all of the same height and width.

The corner blocks C are preferably of greater length than the other blocks and are 25 each formed with a side wall 13, a side wall 14, an end wall 15, an end wall 16, and a vertical web 17, extending across the block from side to side, so providing an air hollow 18 and a post-receiving hollow 19 which 30 extends vertically through each block C. The post-receiving hollow 19 is of slightly greater length than width so that the web 17 may lie in registration with the end walls of blocks like B or A of adjacent layers. 35 In order to provide for the proper junction of blocks B or A with the corner blocks of their respective layers, each corner block C is provided at its side wall 14 with a pair of spaced triangular flanges 14^a, of cross-section similar to that of the flanges described in connection with the other blocks, the recessed end of a block B or A being fitted over the flanges 14^a of its corner block C, the flanges of the corner blocks being disposed at such distance from the end of each block C that the outside face of the block B or A joined to a corner block will lie in the same vertical plane as the corresponding end face of the joined corner block. By 45 positioning opposite corner blocks C of each layer, as shown at c and c', Figure 1, and placing the corner blocks C of adjacent layers at right angles to each other, as will be seen by comparing the positions of the 50 corner blocks C, Figure 1, and building wall portions between the corner blocks of blocks A and B, joined end to end, with the triangular flanges of one block fitted into the recessed end of an adjacent block, a very 55 strong and durable structure may be produced; each corner block C has a recessed formation at its end wall 15 corresponding to the formation of the recessed ends of the blocks A and B, so that the flanged ends 60 of blocks A or B may be joined thereto to

continue the respective layer from the recessed end of the corner block. By so forming and laying the corner blocks and their adjacent blocks B or A, a corner post-moulding space corresponding to the conformation of the post shown at E, Figure 4, is produced and the corner post of cementitious material when poured therein, after the laying of several courses, or upon completion of the laying of all the wall blocks, 70 will have the form illustrated, each corner block being actually interlocked with the post by having a key 20 of the post lying against its side wall 14 and between the flanges thereon, and by having one of the 75 rectangular portions 21 of the main body of the post passed through and filling the rectangular post-receiving orifice in such corner block C. The rectangular relation of the 80 corner blocks, with the overlying and interposed blocks B or A, coupled with the advantage of the interlocked corner post, provides for a structure of great stability. 85

By joining one of the relatively short blocks B to the side of the corner blocks, 90 the flange-carrying end wall of the block B will lie in the vertical plane of the recessed end wall of the corner blocks of adjacent layers, and by properly laying other blocks A end to end with the corner blocks 95 and the blocks B, the blocks may be laid with the joints of alternate layers staggered, and with post-receiving or post-molding openings, of all the layers in registration, the blocks of one layer extending from the 100 respective corner block, having their flanged ends pointed in the same direction as the recessed ends of adjacent layers. Furthermore, a wall so constructed has a series of air spaces each formed by the registering air 105 hollows of the succeeding layers of blocks.

A special type of block, shown at H has both its ends recessed so that one end may receive the triangular flanges of an adjacent block, while the other end provides a recess in registration with the recessed end of a block of an adjacent layer, to the end that a window or door frame may be fitted into an opening provided in a structure wall, as shown in Figure 1. Such 110 frame may comprise side members 21 each carrying blocks 22 adapted to be fitted into the recessed ends of blocks at the opening and held in place by a transverse bottom sill 23 and a similar sill member which may 115 be provided at the top of the frame. 120

The top course of a structure may comprise blocks D, which may be made to conform to the types A, B and C, but which have their air hollows closed at the top 125 by a top wall d', to the end that, if desired, a structure may be built up of blocks, with its top course of blocks D, a mold applied, and top sill G of cementitious material, such as concrete grout, poured therein, and into 130

the post-receiving openings in the wall at the same time, so uniting all parts of the structure. A member 25 adapted to have ceiling or roof members secured thereto may 5 be embedded in the sill if desired. In cases where the sill is not provided, I pour the grout forming the cementitious posts directly into the vertical post-receiving openings formed between adjacent blocks, 10 and in the corner blocks, filling such openings to the top of the wall, and the cementitious posts upon setting bind the several layers through which they pass together.

The foundation may be formed in any 15 suitable manner, the form shown having a groove or channel 26 in its upper face, and in registration with the openings of the first layer of blocks which are laid directly upon such upper foundation face and which 20 may be united thereto by pouring cementitious material into the blocks partially filling such lower blocks and the channel. In pouring the posts, the material thereof is caused to unite with the material keying 25 the lower course or layer of blocks to the foundation.

Suitable vertical reinforcing rods 27 may be placed in the post-receiving openings before filling the same, and horizontal 30 reinforcing rods 28 may be placed in the structure if desired; to this end, I form certain of the blocks, or all blocks, if desired, with semi-circular notches 29 in walls thereof, and as best shown in Figures 2 and 3, these notches are preferably located at the top of the end walls of the blocks, extending inwardly to a thin wall portion 30, and to a depth corresponding approximately to the thickness of the 40 reinforcing rod. Where a horizontal reinforcing rod is to be used, I break down the thin wall portions 30 with a hammer or other implement and so provide a space in the end walls to accommodate the rod which 45 may extend longitudinally throughout a layer of blocks as shown at 31, Figure 1.

In Figure 6, I have shown blocks suitable for building silos or other structures with circular or curved walls; these blocks differ 50 from the blocks A principally in that each is formed with one long and one short side wall, and in that the recessed and flanged portions are suitably formed to allow for end-to-end interfitting of blocks slightly angularly related.

In practicing my invention, I preferably make the flanges of sufficient length to have their tops lie against the corresponding converging walls of adjacent blocks at a point 60 approximately midway of the length of such walls, so producing a post-molding opening of proper symmetrical figure, and the posts poured therein will have corresponding symmetrical cross-sections, and will preferably be thicker transversely of the wall than 65

lengthwise thereof, and the surfaces of a post contacting and bonded with adjacent blocks will be approximately equal.

Having thus disclosed my invention, I claim and desire to secure by Letters Patent:

1. A building construction comprising a plurality of superposed layers of interfitting blocks formed at their interfitting portions with openings producing post-receiving 75 openings between adjacent blocks of the same layer, certain of said blocks being corner blocks angularly placed with respect to corner blocks of adjacent layers and each formed with a post-receiving opening communicating with the post-receiving opening of the corner block of an adjacent layer and with the post-receiving opening formed between said last named corner block and another block of the same layer fitted 85 thereto.

2. A building construction comprising a plurality of superposed layers of interfitting blocks formed at their interfitting portions with openings producing post receiving 90 openings extending vertically through successive layers between adjacent blocks of the same layer, certain of said blocks being corner blocks angularly placed with respect to corner blocks of adjacent layers and 95 each having a post-receiving opening, and a post of cementitious material disposed in said corner block openings and extending from layer to layer and having integral keys disposed in the post-receiving openings 100 formed between said corner blocks and other adjacent blocks.

3. A building construction comprising a plurality of superposed layers of hollow interfitting blocks formed at their interfitting portions with openings producing post-receiving 105 openings between adjacent blocks of the same layer, certain of said blocks being corner blocks of greater length than width and being angularly placed with respect to 110 corner blocks of adjacent layers and being each formed with a rectangular post-receiving opening extending across the corresponding opening of the corner blocks of adjacent layers and the post-receiving openings 115 formed by said last named corner blocks and other blocks fitted thereto, and a post of cementitious material having a main portion filling said post-receiving openings in said corner blocks and extending from layer 120 to layer and having integral key portions each filling the post-receiving space between one of said corner blocks and one of said other blocks fitted thereto whereby an interlocking relation of post and corner blocks 125 is had.

4. A building construction comprising a plurality of superposed layers of hollow interfitting blocks formed at their interfitting portions with openings producing post-re- 130

- ceiving openings between adjacent blocks of the same layer, certain of said blocks being corner blocks of greater length than width and being angularly placed with respect to corner blocks of adjacent layers and each having a post-receiving opening extending across the corresponding opening of other corner blocks, and certain of said blocks being wall blocks and having end-to-end interfitting engagement each with another and so producing continuous vertical post-receiving spaces extending from layer to layer, a cementitious post in the post-receiving openings of the corner blocks, a cementitious post in each of said continuous post-receiving spaces, and a sill formed integrally with and uniting all of said posts. 60
5. A hollow building block having side and end walls, one pair of oppositely disposed walls each having alined notches extending partly therethrough, said walls having frangible portions in line with said notches. 70
- 20 6. A wall construction comprising hollow blocks arranged end to end, the ends of said blocks having frangible portions in line with openings extending partly therethrough, the frangible portions of a plurality of successive block ends being broken away and forming successive alined channels, and a reinforcing rod received in said channels. 80
- 25 7. Hollow building blocks having interfitting formations; said formations being respectively a recessed formation of one of said blocks at one of the walls thereof and a plurality of flanges of triangular cross-section on one of the walls of the other of said blocks; said recessed formation having converging walls adapted for engagement by the outer faces of said triangular flanges when the blocks are assembled, so providing a symmetrical post-receiving and molding hollow space in addition to but separate from the hollows of the blocks; said triangular flanges being of such length that each covers only a part of the corresponding converging wall and whereby the 90
- 30 50 symmetrical post-molding space is produced between the inner surfaces of the triangular flanges and the wall surface lying between them presented to the post by one of the blocks, and the similar opposed surfaces of the other of the blocks and comprising the portions of the converging walls not covered by the flanges and the wall surface ly- 100
- 95 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000
- ing between the converging walls, whereby when a post is poured, it extends through successive courses. 60
8. A wall construction comprising a plurality of superposed layers of interfitting building blocks, each layer comprising a series of said blocks, and each of said blocks having interfitting engagement with an adjacent block of its series whereby building hollows are produced in each layer and in registration with corresponding building hollows of adjacent layers; and posts extending throughout a plurality of successive layers and disposed in said building hollows, each post having a portion within the end of each adjacent block. 65
9. A wall construction comprising a plurality of superposed layers of interfitting building blocks, each layer comprising a series of said blocks, and each of said blocks having an air hollow in registration with the corresponding air hollow of a block of an adjacent layer and being formed for interfitting engagement with an adjacent block of its series whereby building hollows are produced in each layer and in registration with corresponding building hollows of adjacent layers; and posts of cementitious material in said building hollows and extending throughout a plurality of the layers. 75
10. A wall construction comprising a plurality of superposed layers of building blocks, each layer comprising a series of blocks each having an opening extending upwardly therethrough in registration with the corresponding opening of a block of an adjacent layer, each having spaced projections at one end and more widely spaced projections at the other end, all of the blocks of one layer being laid in the same direction with the projections at one end of each block fitting between the more widely spaced projections of the next block and the blocks in each layer being arranged in the direction opposite to that of the blocks of the adjacent layer whereby broken joints are produced, and posts between the interfitting projections of the adjacent blocks and extending throughout a plurality of layers. 90
